UNITED STATES PATENT OFFICE.

NICHOLAS C. MARIEN, OF CHICAGO, ILLINOIS.

AIR WASHER.

Application filed November 3, 1923. Serial No. 672,484.

To all whom it may concern:

Be it known that I, NICHOLAS C. MARIEN, a citizen of the United States, and a resident of Chicago, in the county of Cook and State of Illinois, have invented certain new and useful Improvements in Air Washers, of which the following is a specification.

My present invention embodies improvements in air washers over that set forth in my co-pending application for Letters Patent for improvements in air washers, Serial No. 623,830, filed March 9, 1923, and like the invention disclosed in my said application, relates generally to improvements in air moistening, dehumidifying and purifying apparatus.

In a general way, the object of my present invention is substantially the same as that set forth in the aforesaid pending application, to wit: the production of an apparatus of the above named general character, which shall be simple and inexpensive in construction, compact in form, and highly efficient in operation, wherein and whereby a continuous current or volume of air, which may or may not previously or afterwards, have its temperature raised or lowered, is beneficially treated and caused to flow through a conduit or casing and be delivered to a suitable place or places for any desired purpose.

Specifically, my present invention is directed to an improved construction and arrangements of parts over the structure and arrangement of the parts of the aforesaid pending application, whereby the capacity of the apparatus will be greatly augmented over that of my aforesaid invention, or, in other words, a greater quantity of air can be treated by the apparatus embodying the present invention and more efficiently than by the apparatus disclosed in my said application, without unduly increasing the dimensions of the parts of the device.

I accomplish the last named objects or results by an improved construction of the moisture eliminating element of the invention as well as by the arrangement and construction of certain parts of the device which co-operate with said elements.

The invention consists in certain peculiarities of the construction, novel arrangement and combination of the various parts thereof, as will be more readily explained and understood when read in conjunction with the accompanying drawings, in which an embodiment of which the invention is sus-

ceptible is illustrated, it being understood that changes and modifications may be resorted to without departing from the spirit of the invention so long as they fall within the scope of the appended claims.

In the drawings,—

Fig. 1 is a central vertical longitudinal sectional view through the conduit or casing showing the blower casing of the device in elevation.

Fig. 2 is a view partly in section and partly in elevation taken on line 2—2 of Fig. 1 looking in the direction indicated by the arrows.

Fig. 3 is a similar view taken on line 3—3 of Fig. 1 as indicated by the arrows.

Fig. 4 is an inner view of a portion of the periphery or rim of an eliminator for removing water and impurities from the air as it passes through the apparatus, showing in section the construction of one of the vanes or blades of said eliminator, the view being taken on line 4—4 of Fig. 3, and

Fig. 5 is an enlarged view partly in section and partly in elevation taken on line 5—5 of Fig. 1 as indicated by the arrows, showing an improved means for spraying or distributing water near the inlet end of the apparatus.

Corresponding numerals of reference refer to like parts throughout the different views of the drawings.

The conduit or casing of the device is designated as a whole by the numeral 10 and is herein shown as being rectangular in cross-section and of an elongated shape. This casing may be made of any suitable size and material but by preference of sheet metal and has its inlet end open from its top to a point at a desired distance above its bottom or floor as at 10^a, see Fig. 1 of the drawings. By terminating the opening in the front end of the casing at a distance above the bottom thereof, it is apparent that a compartment 100 for holding water 11 will be provided at the lower portion of the casing. The discharging end of the casing is provided with an inwardly extended flange 12, the free edge of which forms an opening 13 for communication with a blower casing designated as a whole by the numeral 14 which may be suitably mounted on the rear end of the casing 10 but for communication therewith as above stated.

As will be observed in Fig. 1 of the drawings, the casing 10 is provided rearwardly of

its longitudinal middle with a transverse partition 15, thereby dividing the casing 10 into two chambers or compartments 16 and 17, the latter being of less depth than the 5 former or front compartment and has its floor forwardly and downwardly inclined from the front portion of the blower casing 14 as at 18, see Fig. 1, to the rear wall of the compartment 16 to which said floor is 10 secured at a point a suitable distance above the floor of the chamber 16 for the purpose to be presently explained.

Just above the floor 18 and at the front edge thereof, the partition 15 is provided 15 with one or more openings 19 for the passage of water from the inclined floor 18 to the container 20 for water in the lower portion of the chamber 16, which container has vertically mounted therein at about its middle 20 an overflow pipe 21 for the discharge of water when a sufficient quantity thereof has accumulated in the container 20 to enter the upper end of said pipe.

Transversely journaled in the blower 25 casing 14 and extended through the casing 10 is a rotary shaft 22 which is journaled at its end opposite the blower casing 14 on the upper portion of a standard 23 which may be supported on the floor of the chamber 30 16 of said casing. This shaft may be driven by any suitable means but in the present instance is shown as being equipped at its end adjacent the blower casing 14 with a pulley 24 to which a belt may be applied 35 for transmitting power thereto from any suitable source.

Mounted on the shaft in the blower casing is a fan 25 of any preferred construction, which is employed to create and maintain 40 a current or volume of air through the conduit or casing of the apparatus and to force said current through an outlet 26 of the blower casing, from whence it may be conducted to any suitable place or places 45 and used for the desired purpose.

One of my improved water or moisture eliminating elements is mounted in the compartment 16 of the casing and comprises a hub 27 secured to the shaft 22 so as to rotate therewith and having a series of blades 50 or vanes 28 radially extended therefrom and set at angles diagonally disposed with respect to the shaft 22, is employed for removing moisture and impurities from the 55 current of air as it passes through the apparatus. Each of these blades or vanes 28 is made of flat material and fan shaped with its wider portion or outer end located against and secured to the inner surface of 60 the circular rim or annulus 29 which is of less diameter than the diameter of the casing, so that the eliminator may be freely rotated within the casing without contact therewith. This rim or annulus, when the 65 eliminator is mounted on the shaft 22, has

a rearward annular extension 30 which closely surrounds yet without contacting therewith, a forwardly extended annular flange 31 on the front surface of the partition 15, which flange surrounds an opening of its size in the said partition as will be readily understood by reference to Fig. 1 of the drawing, in which view it will be seen that the rear edges of the outer portions of the blades 28 terminate short of 75 the rear end or edge of the rim 29, or in other words, are located just in front of the front edge of the flange 31 carried by the transverse and vertical partition 15. Mounted on the inner surface of the rim 29 at the rear edges of the blades 28, is an 80 annular cleat or baffle member 32 which is inclined forwardly as is clearly shown in Figs. 1 and 4 of the drawings whereby an angular trough-like structure will be provided around the inner periphery of the rim 29 just forwardly of the front end of the flange or annulus 31. On that side of each blade 28 adjacent the cleat or baffle member 32 a series of spaced fins or ribs 33 are 85 longitudinally secured in such a way as to have a slight inclination towards the member 32 yet so as to be disposed at acute angles to the surface of the blade 28 on which they are mounted, these acute angles 90 being located on that side of the members 33 adjacent the front end of the rim 29 of the eliminator wheel. Mounted on the opposite surface of each of the blades 28 and longitudinally thereof are a series of spaced 95 fins or ribs 34 which are disposed at substantially right angles to the front edge or end of the member 32 yet so as to form acute angles between said members 34 and the adjacent surface of the blade 28 on which they are mounted. The above named 100 construction is clearly shown in Fig. 4, in which view it will be observed that the adjacent edges of the members 33 and 34 are so disposed and secured to the blade 28 105 as to form corners of rectangular figures when viewed in cross-section. At the apex of each of these figures the rim 29 is provided with an opening 35 each of which 110 openings is of sufficient size to be common to the angular spaces on each side of the blade 28 or in other words of such size as to provide an outlet through the rim 29 on each side of said blade.

As shown in Fig. 3, the fins or ribs 34 of each blade 28 are spaced substantially in parallelism with one another and on account of the fan shape of the blades 28, the intermediate ribs or fins are consecutively shortened so that they can be thus positioned on the blades. The same arrangement is carried out with reference to the fins or ribs 33 on the opposite side of each blade.

Mounted on suitable brackets 36 extended 130

upwardly from the floor of the chamber 17 of the casing 10 is a cone-shaped water eliminating element 37 which is by preference hollow and made of sheet metal. This 5 cone-shaped member surrounds the shaft 22 concentrically as shown in Fig. 1 directly in front of the opening 13 in the flange 12 of the rear end of the casing 10 and has its front tapered end located at the rear 10 end of the flange 31 and concentrically therewith. The member 37 has at its enlarged upper rear portion an outwardly and forwardly disposed flange 38 located eccentrically with respect to the axis of 15 the member 37 as will be readily understood by reference to Fig. 2 of the drawing. The lower portion of the cone-shaped member 37 is provided at its rear edge with a forwardly and inwardly extended flange 39, which flange, together 20 with the lower rear portion of the member 37, forms a trough-like receptacle for the collection and guidance of water collected by the flange 38 and the upper side portions 25 of the flange 39. Communicating at one of its ends with the trough or receptacle provided by the flange 39 is a pipe 40 which is extended at its other end through the opening 19 in the partition 15 just above 30 the floor 18 of the rear chamber of the conduit or casing. This pipe 40 also extends through an opening in a baffle 41 located on the floor 18 of the rear chamber of the casing rearwardly of the partition 15 and 35 said baffle is employed to prevent water discharged by the pipe 40 being forced back into the said chamber.

Mounted on the shaft 22 near its front end, is a spraying wheel which is quite 40 similar to the spraying wheel shown and described in my aforesaid pending application, and is designated as a whole by the numeral 42 and comprises a hub 43 which may be fixed to the shaft 22 so as to rotate 45 therewith, by any suitable means. Extended radially but forwardly from the hub, or rather towards the inlet end of the casing or conduit, are a plurality of spaced spokes 44 which are united at their outer 50 portions by a band 45 which has the same inclination as the spokes 44 and is provided on its inner surface with a series of diagonally disposed spaced blades 46, (see Fig. 5) which extend inwardly from the band 55 45 and forwardly thereof towards the inlet end of the conduit or casing as is clearly shown in Fig. 1 of the drawing. The inner edges of the blades 46 terminate a distance from the shaft 22 and it will be understood 60 from the above description that the spraying wheel is of an overhanging type. Mounted around the shaft 22 preferably within the space provided by the overhanging blades 46 of the spraying wheel, is a 65 water distributing or ejecting member 47 which is preferably in the form of a tubular ring and has in its outer periphery a series of small perforations 48 for the discharge of water from said ring or member. This water distributor or ejector is supported in a fixed position around the shaft 22 but independently of its movement by means of a water supply pipe 49 which has communication through one of its ends, 70 with the member 47 and at its other end with a supply of water under pressure not shown. This supply pipe may be supported on the standard 23 which supports one end of the shaft 22 by being extended through a suitable opening in the upper end 75 of said standard.

The operation of the device is as follows:—The shaft 22 carrying the fan 25 and the rotary eliminator so as to rotate with said shaft, is driven as before stated, by 80 power applied through any suitable means but usually by means of a belt supplied to the pulley 24 on said shaft. The rapid rotation of the fan and rotary eliminator will create and maintain a continuous current of air entering the inlet end of the conduit, through the same, and said conduit will be discharged from the fan casing 14 through its outlet 26 from whence it may be conducted to any suitable point or places. 85 In this operation it is evident that the spraying wheel 42 will also be rapidly rotated by means of the said shaft. Now, assuming that a supply of water under pressure is admitted to the water distributing or ejecting member 47, it is manifest that it will be forced through said distributor in radially disposed jets or small streams with which the blades 46 of the spraying wheel will contact and act to force 90 the water in spray or mist-like condition circularly at the inlet end of the casing or conduit. As the blades 46 of the spraying wheel 42 are diagonally disposed on the inner surface of the band 45, which band is flared towards the inlet end of the casing, the water will be more effectually driven forwardly by the action of said wheel than if the said blades were located 95 radially on said band, as in my above named application. The current of air passing into the conduit will be subjected to the spray or mist-like sheet of water created by the rapidly rotating spraying wheel 42, and will absorb a quantity of the same. In 100 the further progress through the casing of the air, it will contact with the rotating blades 28 and the fins 33 and 34 on opposite sides of each of said blades and through 105 centrifugal action, the water and impurities will be forced outwardly along the surfaces of the blades 28 and adjacent surfaces of the fins or ribs 33 and 34 until the rim 29 of the wheel is reached, from whence they 110 will pass through the openings 35 therein 115 120 125 130 135 140

and be discharged into the chamber 16 and precipitate into the water container 20 of said chamber.

After the air has been subjected to the action of the blades 28 and their fins or ribs, the current thereof will pass through the opening provided by the flange 31 in the partition 15 and impinge against the cone-shaped water eliminator 37 on which it will 10 travel rearwardly and outwardly from the tapered portion of said member until it strikes the flanges 38 and 39, from which it will pass around the enlarged end of the coneshaped eliminator and rearwardly out 15 through the opening 13 in the rear end of the casing and from thence into the fan from which it will be discharged through the outlet of the latter. In this operation of the current of air on the cone-shaped 20 eliminator, it is manifest that moisture or water contained therein will be extracted therefrom and caused to collect in the trough-like portions provided by the flanges 38 and 39, from the latter of which the water 25 will be drained through the pipe 40 into the water container 20 of the front chamber of the casing.

It is further apparent that in the rapid rotation of the eliminator wheel, the water 30 collected by the baffle or member 32 will be discharged through the openings 35^a formed in the rim 29 at the adjacent edge of said flange.

Having thus fully described my invention, what I claim as new and desire to secure by Letters Patent is:

1. An air washer including in combination with a casing, a rotatable shaft located longitudinally therein, an eliminator wheel 40 mounted on and to rotate with said shaft within said casing said wheel comprising a plurality of spaced radial blades each set

at an angle to its axis and provided with a peripheral rim connecting the outer ends of said blades, the said rim having a plurality of spaced openings arranged in a row at the outer end of each of said blades, said openings being of sufficient size as to each afford outlets on opposite sides of each of said blades, a plurality of spaced fins longitudinally mounted on each surface of each of said blades and connected at their outer ends to the inner surface of said rim, the said fins being disposed at acute angles in the direction of the rotation of the wheel with respect to their blades and connected to the same in pairs at the rear portion of each of said openings in the rim, and a forwardly inclined annular cleat or baffle member secured to the inner surface of said rim at the rear outer portions of said blades, said rim having a series of spaced openings at the adjacent edge of said baffle.

2. An air washer including a casing for the passage of air and a rotatable shaft 65 located longitudinally therein, means in communication with an end for creating and maintaining a current of air through the casing, an imperforate cone-shaped moisture eliminating member fixedly mounted within said casing in front of its discharge opening with its tapered end disposed forwardly of said casing, said member having at the upper rear portion of its periphery a forwardly and outwardly extended flange and at the rear lower portion of its periphery a forwardly and inwardly extended flange forming a trough-like receptacle on said last named portion of said member, and a pipe extended at one of its 70 ends through the last named flange for draining water therefrom.

NICHOLAS C. MARIEN.
